UNITED STATES PATENT OFFICE.

ELIZABETH KOLLER, OF BLOOMVILLE, OHIO.

DESIGN FOR A FRUIT-JAR SHIELD.

SPECIFICATION forming part of Design No. 27,383, dated July 20, 1897.

Application filed June 8, 1897. Serial No. 639,929. Term of patent 14 years.

To all whom it may concern:

Be it known that I, ELIZABETH KOLLER, a citizen of the United States, and a resident of Bloomville, in the county of Seneca and State of Ohio, have invented and produced a certain new and useful Design for a Shield for Fruit-Jars; and I do hereby declare that the following is a full, clear, and exact description of the invention, which will enable others skilled in the art to which it appertains to make and use the same, reference being had to the accompanying drawings, which form a part of this specification.

My invention relates to a novel design for a shield for fruit-jars for preventing the juice or the articles being canned from dropping or splashing on the top of the jar.

The leading feature of the design consists in the general shape or configuration given to the shield, as will be hereinafter fully set forth and described.

In the accompanying drawings, Figure 1 is a perspective view of a fruit-jar shield constructed in accordance with my invention. Fig. 2 is a central vertical section of the same.

In the said drawings the reference-numeral 1 designates a cap, comprising the top 2, having a central circular opening therein and a depending annular rim 3. Connected with said top is a tube or small cylinder concentric with said rim and with its lower end flush with the lower edge of the rim.

The numeral 4 designates a handle, comprising the horizontal portion 5, formed with parallel grooves 6, and the vertical portions 35 7, connected with said cap.

Having thus fully described my invention, what I claim is—

The design for a fruit-jar shield substantially as herein shown and described. 40

In testimony that I claim the foregoing as my own I have hereunto affixed my signature in presence of two witnesses.

ELIZABETH KOLLER.
